[57] CLAIM

The ornamental design for a key handle, as shown and described.

DESCRIPTION

FIG. 1 is a top plan view of a key handle showing my new design, the broken-line disclosure of a key blank being for illustrative purposes only and forming no part of the claimed design;

FIG. 2 is a side elevation view of the design of FIG. 1, seen from the bottom of FIG. 1.

FIG. 3 is a side elevation view of the design of FIG. 1 viewed from the top of FIG. 1.

FIG. 4 is an end elevation view of the front of the design of FIG. 1, viewed from the left of FIG. 1, omitting illustration of the key blank.

FIG. 5 is an end elevation view of the rear of the design of FIG. 1, viewed from the left of FIG. 1.

FIG. 1

FIG. 4

FIG. 2

FIG. 5

FIG. 3
